UNITED STATES PATENT OFFICE.

HENRY J. BUSH, OF WESTFIELD, MASSACHUSETTS.

IMPROVEMENT IN WHIP-LASHES.

Specification forming part of Letters Patent No. 137,341, dated April 1, 1873; application filed January 16, 1873.

To all whom it may concern:

Be it known that I, HENRY J. BUSH, of Westfield, of the county of Hampden and State of Massachusetts, have invented a new and useful Improvement in Lashes for Whips, or in the manufacture thereof; and do hereby declare the same to be fully described in the following specification and represented in the accompanying drawing, of which—

Figure 1 denotes a transverse section of a lash made in accordance with my invention. Fig. 2 is a view of a portion of it with the outer covering or braiding removed. Fig. 3 shows a portion with the braiding in place. Fig. 4 is a view of the lash complete. Fig. 5 is a front view, and Fig. 6 a lengthwise section, of its snapper, showing how the longitudinal strands are disposed to aid in making the edge or loop.

In carrying out my invention I combine, with the outer braiding or braided covering and the cotton or linen swell or body, a series of separate threads or lines arranged at or about at equal distances apart, transversely about and against the swell or body, and running lengthwise thereof or throughout the lash, and so as to entirely surround and cover the swell or body of the same evenly and smoothly, as clearly shown in Figs. 1 and 2, or substantially so, and covered by the braided covering. These threads serve to greatly strengthen the lash to prevent it from stretching so as to draw the braiding apart in a manner to expose the cloth body, as well as to form a surface finished smooth and even about said cloth body upon which to lay the braiding; and they also serve as a convenient means of connecting a snapper to the lash. The cloth swell or body is usually made of a piece of cotton or linen cloth, cut of the proper shape, and rolled up spirally and loaded with clay to give it weight and the necessary form, after which it is introduced into a braiding-machine, and has a covering braided upon it, all of which is well

understood by makers of such kinds of lashes. It is with such a cloth swell or body and its covering that I employ the series of threads to go between them and lengthwise of the lash.

In the drawing, *a* denotes the "swell" or body; *b*, the covering or braiding; and *c c c*, &c., the strengthening-threads, there being about twenty-four in number for a lash of medium size. The threads are to be suitably supported and arranged so as to be laid evenly and at proper distances apart upon the body during the process of braiding the covering, the braiding going directly about the threads and body, and binding the threads firmly in place. These threads may be made of linen, cotton, silk, or other suitable material.

I am aware of the lash described in the United States patent No. 131,975, granted to John C. Schmidt, and make no claim to such, its construction being entirely different from my lash. In the Schmidt lash the whole swell or body, irrespective of the braided cover, is composed of a mass of strips or strands of hide; but in my lash I use what is termed a rolled-cloth swell or body, as employed in making other lashes; and in order to strengthen such, and aid in the formation of the loop *l* at the head of the lash, and provide a means of attachment of the snapper, I combine with such body and the braided cover the series of threads *c*, going through the entire lash, and arranged about the swell in manner set forth.

What I claim as my invention is—

A whip-lash composed of a rolled-cloth body or swell, *a*, with surrounding even-laid longitudinal threads *c* entirely covering the same, and an exterior cover of braid, *b*, substantially as herein shown and described.

HENRY J. BUSH.
